UNITED STATES PATENT OFFICE.

MATTHEW ADAM, OF PHILADELPHIA, PENNSYLVANIA.

HOOK AND EYE.

SPECIFICATION forming part of Letters Patent No. 599,758, dated March 1, 1898.

Application filed May 27, 1897. Serial No. 638,361. (No model.)

To all whom it may concern:

Be it known that I, MATTHEW ADAM, of Philadelphia, in the State of Pennsylvania, have invented a certain new and useful Improvement in Garment Hooks and Eyes, whereof the following is a specification, reference being had to the accompanying drawings.

In said drawings, Figure 1 represents a top or plan view of the hook and eye in engagement, Fig. 2 being a view of the same in side elevation.

The object of my invention is to provide a hook and eye which shall admit of being readily fastened or unfastened when force is intentionally applied thereto and which shall resist accidental movements tending to unhook the eye, and the construction being such as to present no projecting sharp points or ends of wire, and the parts all lying substantially flat when engaged.

Referring to the drawings, A represents the hook, and B the eye, each of which is provided with the usual thread-eyes a a and b b, respectively. The sides of what would in an ordinary hook be termed the "shank" of the hook are bowed laterally outward, as indicated at C C', forming curved springs, and as they approach the bight or bend D are curved rearwardly—that is, toward the body of the person—as seen most clearly in Fig. 2.

Intermediate between the sides C C' is the part E, which by analogy would be termed the "bill," but which differs from the usual bill of a hook in that in the present instance it lies substantially flush with the sides, instead of rising above the same, and is bent in correspondence with the rearward bending of that portion of the shank which is proximate to the bight. The sides of the bill itself are bowed or arched outwardly, as indicated at e e', forming a double incline on each side with a somewhat flat angle, so as to afford an easy riding-surface for the engaging portion of the eye. At the base of the bill, where the sides merge into the bight D, they are separated by a small interspace.

The eye as a whole is indicated at B, the engaging portion or loop thereof F being situated at the end of the two shanks f f', which diverge laterally therefrom. The spread of these shanks at the region of the thread-eyes

gives a comparatively wide base for attachment, and thus insures a firm support. The loop F is also curved rearwardly in a manner substantially corresponding with the curve of the hook near the bight D, the bending of the eye being preferably a trifle more prolonged than that of the hook and the curve near the end beak slightly more abrupt where great accuracy of adjustment is desired. By thus correspondingly curving the bight ends of the hook and eye, respectively, the bight of the eye will pass into contact with the two bights of the hook and pull thereon, and the curvature is such that when thus engaged the body of the hook and the body of the eye will lie in the same longitudinal plane. These curves will not weaken the hook and eye, as would bends at right angles. Moreover, the rearward curvature of the eye permits it to enter the space within the bow C C' in front of the bill E, where it may be readily engaged with the bill.

The intermediate space between the proximate faces f f' of the loop F is less than the distance between the outside portions of the sides e e' of the bill, so that in the act of hooking or unhooking the parts must yield. This yielding may be accomplished through the bending together of the two sides of the bill alone, or it may be aided by the slight outward bending of the two sides of the loop; but in either case the movement, though quite minute, is an entirely positive and appreciable one, so that a distinct though slight effort is required to either hook or unhook the loop.

The bill E terminates within the bow C C', so as not to overlie the fabric where the ears a a are stitched, and thus the eye F may be readily engaged with the bill without the necessity of raising the bill into a higher plane than the bow, as would be necessary if the bill should be extended back to the stitching-points a a.

It will be observed that the line of the wire which forms the hook affords just the proper conditions for developing a true spring action, since, while it is in no wise exaggerated in size, there is a relatively large expanse of wire so disposed as to distribute the total bending required for hooking or unhooking and at the same time obviate the liability to permanent

distortion, the sides, both of the bill and of the shank proper, acting as curved springs and bending in a definite as distinguished from an irregular or indeterminate way.

5 I am aware that it is not new in devices of this character to spring the loop of the eye over obstacles or enlargements popularly known as "humps," and I do not broadly claim the same. Furthermore, I am aware a reéentrant bill is not new, and I do not broadly claim such method of construction.

I claim—

The combination with the hook having the sides of its shank beyond its stitching portions bowed outwardly, and a bill having dou-

ble inclines on its sides and lying flush within the bowed portion; the bight ends of the hook being curved rearwardly, of an eye having a loop of less diameter than the maximum width of the bill and curved rearwardly at its closed end to correspond with the curvature of the bights of the hook, thereby permitting it to engage and pull on the said bights, and said curved portions also permitting the bodies of the hook and eye to lie in the same longitudinal plane; substantially as described.

MATTHEW ADAM.
